WORKPIECE RELEASING DEVICE FOR A STAMPING PRESS

Hershel E. Hicok, % Arbor Tool Corp., 2221 Arbor
Blvd., Dayton, Ohio 45439

Filed June 19, 1970, Ser. No. 23,577

Term of patent 14 years

Int. Cl. D15—99

U.S. Cl. D55—1

FIG. 1 is a perspective view of my new design for a workpiece releasing device for a stamping press;
FIG. 2 is an edge view thereof;
FIG. 3 is a side view thereof;
FIG. 4 is a top view thereof; and
FIG. 5 is a bottom view thereof.

I claim:

The ornamental design for a workpiece releasing device for a stamping press, substantially as shown and described.
